RECIPROCATING TOOL ATTACHMENT FOR A POWER TOOL UNIT

Thomas B. Keesling, Los Gatos, Calif.

Application April 25, 1952, Serial No. 19,469

Term of patent 14 years

(Cl. D54—13)

To all whom it may concern:

Be it known that I, Thomas B. Keesling, a citizen of the United States, residing in the city of Los Gatos, county of Santa Clara, State of California, have invented a new, original, and ornamental Design for a Reciprocating Tool Attachment for a Power Tool Unit, of which the following is a specification, reference being had to the accompanying drawing, forming a part thereof.

Referring to the drawing:

Figure 1 is a side elevational view of a reciprocating tool attachment for a power tool unit, showing my new design.

Figure 2 is a bottom plan view of the tool.

Figure 3 is a side elevational view opposite to that of Figure 1.

Figure 4 is an end elevational view taken from the right of Figure 2.

The essential features of my design reside in the portions shown in full lines.

I claim:

The ornamental design for a reciprocating tool attachment for a power tool unit, substantially as shown and described.

THOMAS B. KEESLING.
